UNITED STATES PATENT OFFICE.

GEORGE P. THOMPSON, OF PRINCETON, ILLINOIS.

UPRIGHT PIANO.

1,196,903.

Specification of Letters Patent. Patented Sept. 5, 1916.

Application filed January 22, 1916. Serial No. 73,559.

To all whom it may concern:

Be it known that I, GEORGE P. THOMPSON, a citizen of the United States, residing at Princeton, in the county of Bureau and State of Illinois, have invented certain new and useful Improvements in Upright Pianos, of which the following is a specification.

This invention relates to upright pianos and has for its object the provision of an instrument, the tone quality of which is superior to that of upright pianos heretofore in common use.

Other objects and advantages of my invention will be apparent as it is better understood by reference to the following specification when read in connection with the accompanying drawing, illustrating the preferred embodiment thereof, in which—

20 Figure 1 is a front elevation of an upright piano according to my invention, the upper front portion of the case being removed for better illustration, and Fig. 2 is a vertical section on the line 2—2 of Fig. 1.

25 In upright pianos, as usually constructed, the upper ends of the strings are disposed in a substantially horizontal line, the strings extending downwardly in varying lengths, depending upon the particular note to be sounded thereby. It is a well-known fact 30 that the tone quality of such pianos is usually inferior to that of pianos of the horizontal type, particularly in the bass section, because of the limitations imposed by the 35 conventional form of upright piano cases.

Referring to the drawing, 1 indicates a case which may be of any suitable form, that illustrated being suggestive of the form of a harp, the tone quality of which is closely 40 approximated by my improved upright piano. A metal string plate 2, to which the strings 3 are anchored, is disposed within the case 1 and the usual sound board 4 is also provided.

45 In order to provide for bass strings of considerably greater length than have heretofore been employed in upright pianos the upper portion of the string plate 2 in my improved upright piano extends upwardly 50 at the bass section of the piano, as is clearly indicated in Fig. 1. The strings 3 in the bass section are anchored to the highest portion of the string plate 2 and extend downwardly obliquely of the plate. By this 55 arrangement I am enabled to provide bass

strings substantially equal in length to those employed in pianos of the horizontal type.

Pivotedly mounted on the support 6 are a plurality of keys 7, each of which is connected by a rod 8 to a member 9, to which is pivotally secured a jack 10. The upper ends of the jacks 10 engage the shanks 11 of the hammers 12, pivotally mounted on a suitable support 13 extending longitudinally of the case 1.

65 The actuating mechanism for the hammers just described is identical in form and mode of operation with that commonly employed in upright pianos.

A rest rail 13 extends longitudinally of the case 1 in front of the hammers 11 and is adapted to be engaged thereby when the hammers return after striking the strings 3.

As will be readily understood by reference to Fig. 1, the hammers 11 are arranged in a line curving upwardly in the central section of the piano so that the hammers which co-operate with the bass strings are considerably higher than those which co-operate with the treble strings. I have discovered that 70 this arrangement of the hammers 11 in combination with the elongated bass strings produces an instrument of much finer tone quality than it has heretofore been possible to attain in an upright piano. The rest rail 75 13 curves upwardly in the central section of the piano to correspond with the position of the action hammers.

80 It will be noted that the shanks 11 of the hammers 12 are pivoted in a horizontal line 90 extending longitudinally of the case 1 and that, therefore, the shanks 11 vary in length, those corresponding to the bass strings being materially longer than those at the treble end of the piano. This arrangement 95 materially aids in producing tones of a superior quality.

It will be apparent that various changes may be made in the form, construction and arrangement of the parts without departing from the spirit and scope of the invention or sacrificing any of its material advantages, the form hereinbefore described being merely a preferred embodiment thereof.

100 I claim:

1. An upright piano comprising a string plate, a plurality of strings secured thereto, a plurality of keys and a plurality of hammers actuated thereby and provided with shanks, said shanks being longer in the bass 110

than in the treble section of the piano, whereby said hammers engage said strings along a line which is farther from the plane of the keys in the bass than in the treble section.

2. An upright piano comprising a string plate, a plurality of strings secured thereto, a plurality of keys and a plurality of hammers actuated thereby and provided with shanks, said shanks being longer in the bass than in the treble section of the piano and

of gradually increasing length in the central section, whereby said hammers engage said strings in a line which is parallel to the plane of said keys at both ends thereof and 15 inclined to the plane of said keys in the central section of the piano.

GEORGE P. THOMPSON.
